UNITED STATES PATENT OFFICE

PAUL A. MEEHAN, OF CLEVELAND, OHIO, ASSIGNOR, BY MESNE ASSIGNMENTS, TO SWINDELL-DRESSLER CORPORATION, OF PITTSBURGH, PENNSYLVANIA, A CORPORATION OF PENNSYLVANIA

ANNEALING FURNACE

Application filed August 23, 1928. Serial No. 301,503.

The present invention relates to kilns and furnaces in which metallic articles are annealed or subjected to other heat treatment tending to produce undesirable surface oxidation. While certain features of my invention are not restricted to use in connection with any particular type of furnace, my invention is especially advantageous when used in annealing metallic bodies in a tunnel kiln through which the articles to be heat treated are passed on cars.

In tunnel kiln annealing operations wherein metallic articles, such as steel sheets used in automobile bodies are passed through the kiln, it is customary to cover the sheets with a box resting in a sand seal at the bottom of the car. When the cars are passed into the kiln and subjected to the high temperatures therein, the gases within the box are expanded and escape through the sand seal or any other openings. When the material reaches a certain temperature, the carbon in the steel reacts with any iron oxide present to form an atmosphere within the box of almost pure carbon monoxide. No oxidation will take place as long as this atmosphere is maintained. After passing the high temperature section the kiln, the gases and articles are cooled and contract. The consequent lowering of the gas pressure within the box permit furnace gases, or if the car is drawn outside the kiln, air, to be drawn into the box. With such an atmosphere within the box the sheets on the top of the pile rapidly oxidize while the lower sheets develop undesirable blue or grey edge portions. Sheets used in automobile bodies require a surface finish of the highest degree and surface oxidation must be eliminated.

Oxidation of the sheets or other metallic articles being annealed can be prevented by maintaining the articles in a reducing atmosphere by introducing reducing gases into the box during the annealing process and preferably before the articles begin to cool. In annealing operations in a continuous tunnel kiln, in which the articles to be heat treated are passed through the kiln chamber on kiln cars, practical difficulties arise in con-

tinuously supplying reducing gases to the annealing boxes on the moving cars.

The object of my present invention is to provide an improved method of and apparatus for supplying a fluid, such as reducing gases, to a kiln car in a continuous tunnel kiln. A further object of my invention is to provide an improved construction of a kiln car, especially adapted to receive a fluid from a source of supply supported on the car or connected thereto in any suitable manner.

The various features of novelty which characterize my invention are pointed out with particularity in the claims annexed to and forming a part of this specification. For a better understanding of the invention, however, and the advantages possessed by it reference should be had to the accompanying drawings and descriptive matter in which I have illustrated and described preferred embodiments of the invention.

Of the drawings:

Fig. 1 is a sectional elevation of a tunnel kiln in which a preferred form of my invention is incorporated;

Fig. 2 is an enlarged elevation of a portion of the apparatus shown in Fig. 1;

Fig. 3 is a section on the line 3—3 of Fig. 2;

Fig. 4 is an enlarged view of a portion of the car showing the gas inlet to the annealing box;

Fig. 5 is a sectional elevation of a modified form of my invention;

Fig. 6 is an elevation partly in section of a second modification;

Fig. 7 is an elevation partly in section of a third modification;

Fig. 8 is an end elevation of the apparatus shown in Fig. 7;

Fig. 9 is a side elevation partly broken away and in section of an enlarged modification; and

Fig. 10 is an end elevation of the apparatus illustrated in Fig. 9.

In the drawings and particularly in Figs. 1 to 4, I have illustrated a preferred embodiment of my invention in which a tunnel kiln A having the usual refractory side walls A¹ and crown A² is provided with a kiln chamber B extending longitudinally of the kiln. 100

The lower portion of the kiln chamber is provided with track rails B' at its bottom for goods carrying cars or trucks C. The kiln is heated by combustion chambers B² resting on benches B³ at the side of the passageway 5 for the body of the car C. The combustion chambers B² through which the burner gases and products of combustion pass lengthwise of the kiln have their heating walls formed with the customary circulating channels 10 through which a convection current circulation of the kiln atmosphere is set up. The kiln chamber is provided at its entrance end with an ante-chamber B⁴ having a door B⁵ between it and the kiln chamber. At the opposite end of the kiln chamber is an exit chamber B⁶ also separated from the kiln chamber proper by a door B⁷. The goods carrying cars are inserted one at a time at the entrance end of the kiln and the train of 20 cars normally filling the kiln is advanced a car length each time a car is inserted by a car pusher (not shown) which may be of any suitable or usual type employed for the purpose. Longitudinally extending pits A³ and A⁴ are provided adjacent the entrance and exit ends respectively, of the kiln, each of the pits being connected to a point externally of the kiln by a lateral tunnel (not shown). Intermediate the pits are one or more cross 25 tunnels A⁵ extending below the kiln chamber and providing access at longitudinally spaced points to the underside of the cars.

Each of the goods carrying cars or trucks 30 C comprises a refractory body portion D consisting of massive blocks of refractory material D' supported on a metallic frame C' on the lower side of which a plurality of pairs of wheels forming the car running gear C² is 35 suitably mounted. Each of the trucks has a cast metal cover plate E extending over and protecting the upper sides of the refractory blocks D'. The cover plate is preferably divided into two sections E' and E² in overlapping relation and each of which is formed on 40 its upper side with a rib E³ extending longitudinally of the car and adjacent the outer edge of the cover plate. A trough shaped groove or channel E⁴ with inclined sides is 45 formed in the upper side of each rib E³. A plurality of roller elements, such as cast iron or steel balls F, are mounted in each of the channels and form a support for a metal work support or tray G which extends over 50 the top of the composite car. The tray is formed on its underside with a pair of downwardly projecting longitudinal ribs G', each of which has a channel G² in which the tops of the balls F are received.

55 The metal plates or other material to be annealed are piled on the tray and are ordinarily covered by a removable metallic cover H which as shown is formed of heavy metal plates riveted together. The cover is in the 60 form of a box with a closed top and open bot-

tom. Hooks H' are provided on the sides of the box H to permit engagement by a suitable hoisting mechanism (not shown) for lowering the box on to and lifting it off the tray. The top of each box H is provided at 70 points adjacent the ends with openings H² closed by removable plugs H³. A sand seal H⁴ surrounds each plug to prevent the escape of the gases from the interior of the box when the plug is in position. The plugs can be removed to permit air within the box to be swept out before the box is passed into the kiln and also to permit the escape of reducing gases after the car passes out of the kiln chamber. A sand seal H⁵ is also provided for sealing the lower edges of the box as shown in Fig. 2.

In my improved form of car one of the center balls has its lower portion F' shaped to fit the inclined sides of the groove E⁴ and shoulders F² resting on the upper surfaces of the cover plate ribs as shown in Figs. 3 and 4. The ball is welded to the rib and provided with a vertical passage F³ therethrough connected at its lower end to an aligned vertical passage D² in the subjacent refractory block D'. A pipe D³ is positioned in the passages D² and F³ and extends upwardly to the center portion of the ball. A fluid nozzle F⁴ is mounted in a vertical recess F⁵ formed in the ball and connected to and in alignment with the passage F³. The nozzle projects upwardly into an enlarged vertical passage G³ formed in the tray G and rib G'. A groove G⁴ extends transversely of the tray beneath 100 the pack of sheets to ensure a proper distribution of the reducing gases. Longitudinal grooves may also be provided if desirable. With this construction any fluid passing upwardly through the pipe D³ will pass into the space enclosed by the box H. A fluid tight connection between the ball and the rib G' is provided by a tray F⁶ mounted on the upper portion of the ball. The space between the tray and lower side of the rib is filled with 105 fireclay, which is supported on the tray. The kiln car construction heretofore described is disclosed and claimed in my divisional application, Serial No. 475,161, filed August 14, 1930.

110 Various means may be provided for supplying a reducing gas such as natural gas, coke oven gas or producer gas to the cars. In the construction illustrated in Figs. 1 to 4 a pipe J is supported beneath the metallic 115 car frame C' and extends longitudinally thereof. This pipe is connected to the vertical pipe D³ by a lateral pipe J' in which a control valve J² is mounted. The pipe J is provided adjacent its ends with cut off valves J³ and J⁴. A T fitting J⁵ to which an inlet valve J⁶ and hose connection J⁷ is attached is positioned in the pipe J. The pipe is also provided with a hose connection J⁸ at one of its ends beyond the corresponding cut-off 120

125 130

valve by which it is connected to the main pipe J of the following car.

The pit A³ adjacent the entrance end of the kiln preferably extends two car lengths longitudinally of the kiln and is provided with a supply pipe K connected to a source of reducing gas. The control valve K' for the supply pipe is provided with a double outlet to which two lengths of hose, 1 and 2 are connected. Each hose has sufficient length to permit it to be connected to the hose connection J⁷ on any of the cars mounted on the tracks above and accessible from the pit A³.

Assuming that the kiln is filled with cars to its capacity and the hose 1 is connected to the hose connection J⁷ on the last car, the pipe J of which has its cut-off valve J³ closed. The hose 1 will then be in the position shown in Fig. 1 and the hose 2 will be disconnected. As the cars are pushed forward one car length and a new car introduced into the kiln chamber, the hose 1 travels forward with the car to which it has been attached into the position occupied by the hose 2 in Fig. 1. The hose connection between the last car, to which the hose 1 is connected, and the new car will then be connected and the rear cut off valve J³ on the last car opened while the rear cut off valve of the new car remains closed. The hose 2 will then be connected to the hose connection J⁷ of the new car and the inlet valve J⁶ to that car opened. When this has been done the train is receiving a supply of reducing gases not only from the hose 1 but also from the hose 2. The hose 1 then being in the forward end of the pit is disconnected and brought back into position to be connected to the inlet hose of the next car to be inserted in the chamber. In this way a continuous supply of reducing gases is delivered to the cars and annealing boxes.

As each car reaches the pit at the exit end of the kiln chamber, the front cut off valve J⁴ on the car passing over the pit is closed and as the rear end of the car passes over the pit the rear cut off valve is closed simultaneously with the front valve of the next car. The hose connection J⁸ between the two cars is then disconnected and the first car passed into the exit chamber where another source of reducing gas is coupled to the hose connection J⁷ to continue the supply of gases to the annealing box.

With the reducing gas supply connections shown and operating as described the annealing boxes may be supplied with reducing gases throughout the passage of the cars through the kiln chamber or only from a point intermediate the ends of the chamber. This point is preferably adjacent the high temperature section of the kiln. A cross tunnel A⁵ is provided at this point to permit access to the inlet valve J⁶ on each car. With this mode of operation a continuous supply of reducing gases passes through the

pipes J and hose connections J⁸ but none of the reducing gases pass into the annealing boxes H until the cars reach the high temperature section of the kiln at which point an operator in the cross tunnel A⁵ opens the inlet valve J⁶ on each car and permit the reducing gases to pass upwardly into the corresponding annealing box.

In the construction illustrated the underside of the car and the operators in the pits are protected from the high temperature chamber atmosphere by plates C³ mounted on the sides of the car frame and extending downwardly into a trough C⁴ filled with sand.

In the modification illustrated in Fig. 5 a different form of apparatus for supplying a reducing atmosphere continuously to the annealing boxes is illustrated. In this construction a tank L filled with a highly compressed gas or volatile liquid such as gasoline, is connected to the underside of the metallic platform C'. The tank has a valved connection L' to the vertical pipe D³. In this modification the fluid nozzle F⁴ is arranged with a relatively small orifice through which the fluid can slowly leak.

When a volatile liquid is used in the tank the rate of evaporation increases as the car reaches the higher temperature sections of the kiln and the rate of evaporation is a maximum in the cooling section of the kiln since the lower portion of the car is at its highest temperature at that point due to the heat soaking down through the car frame. When compressed gas is used the supply tanks may be replenished at longitudinally spaced points along the kiln by means of cross tunnels such as shown in Fig. 1.

In some instances it is desirable to provide a tunnel extending throughout the greater portion of the kiln chamber where access is necessary to the underside of the cars throughout that portion of the kiln. Such a construction is illustrated in Fig. 6 wherein cross tunnels M' are connected to the longitudinal tunnel M beneath the kiln chamber to permit access thereto at longitudinally spaced points.

Another arrangement for supplying reducing gases to the car train is shown in Figs. 7 and 8, wherein a continuous metallic hose N mounted on sheaves N' at each end of the tunnel O which extends substantially the length of the kiln chamber. The hose N is provided with connectors N² at intervals of one car length which are connected to supply conduits N³ on the individual cars. In this arrangement the source of supply of reducing gases is connected to the moving hose by a pair of connectors in the manner described in connection with the forward pit of Fig. 1. As each car is passed into the kiln chamber, it is connected to the metallic hose and at the same time the source of supply is connect-

ed to a new point along the hose which moves with the cars. The connectors N² are preferably provided with cut off valves N⁴.

Still another arrangement is illustrated in Figs. 9 and 10 in which a tunnel P extending throughout the length of the kiln chamber is provided with a pair of tracks Q and Q' at its bottom. Small cars R carrying tanks R' of compressed gas are arranged to move on the track Q. The track Q' is a return track for the cars carrying empty tanks. In this arrangement as each kiln car is inserted, it is connected by a suitable hose connection S to one of the cars R on the track Q which moves through the kiln along with the kiln car. As the kiln reaches the exit end of the kiln the tank car R is detached and returned on the track Q' to the entrance end of the kiln where the tank is refilled.

In some installations, it may be desirable to combine several of the gas supply systems shown. For example, it may be desirable to install a tank car supply system such as illustrated in Figs. 9 and 10 at the exit end of the kiln shown in Fig. 1 so that during the interval when the car is detached from the train and before it is connected to the external gas supply outside of the kiln, the car will be connected to a source of gas supply. The small tank cars can be attached when the main supply of gas is detached and used until the kiln car is connected with the external supply.

The apparatus and method described is primarily designed for the production of steel sheets having the highest degree of finish.

My invention is as applicable for producing what are known as "blue" sheets by passing steam in the same manner into the annealing boxes while the cars are in the cooling section of the kiln.

While in accordance with the provisions of the statutes, I have illustrated and described the best forms of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention what I claim as new and desire to secure by Letters Patent, is:—

1. A continuous tunnel kiln having a goods passageway therein normally closed at its ends and through which kiln cars carrying goods to be heat treated in an inclosed car chamber are passed, means for moving a plurality of cars simultaneously through said passageway, a fixed source of fluid within the entrance end of the kiln and below said cars and means for maintaining a continuous sup-

ply of fluid from said source to said car chambers while said cars are moving through said passageway.

2. A continuous tunnel kiln having a goods passageway therein through which kiln cars carrying goods to be heat treated are passed, a pit below said passageway and adjacent the entrance end of the kiln, a container on said cars arranged to receive a fluid, a fluid supply in said pit, means for passing fluid from said supply to said container, and a second pit at a longitudinally spaced point along said passageway and from which said fluid supply is disconnected from said container.

3. A continuous tunnel kiln having a goods passageway therein normally closed at its ends and through which kiln cars carrying goods to be heat treated in an enclosed car chamber and passed, means for moving a plurality of cars simultaneously through said passageway, a pit opening to said passageway adjacent the entrance end of the kiln, and means for continuously supplying a fluid to said car chambers while in said passageway comprising a fluid supply in said pit and means for connecting said supply to said car chambers.

4. The method of maintaining metallic articles in a fluid atmosphere during heat treatment thereof in a continuous tunnel kiln which comprises enclosing said articles in a substantially air tight receptacle, connecting said enclosed space with a source of fluid at the entrance end of said kiln, and disconnecting said space from the source and closing said space to the atmosphere at the exit end of the kiln.

5. The method of supplying fluid to a train of kiln cars which comprises supplying fluid from a source of fluid to said train, moving said train in a tunnel kiln a predetermined distance and inserting an additional car at one end of said train, and connecting said last mentioned car to said source of fluid and maintaining a continuous supply of fluid to said train during its movements through said kiln.

6. The method of supplying fluid to a series of goods enclosing containers mounted on a train of kiln cars passing through a tunnel kiln which comprises maintaining a continuous supply of fluid to all of said cars, supplying said fluid to each container when said container reaches a predetermined point in said kiln, and disconnecting each container from said supply and closing said container to the atmosphere when it reaches a second predetermined point in said kiln.

7. The method of continuously supplying a fluid to a train of tunnel kiln cars in a tunnel kiln in which the cars are moved intermittently by the insertion of an additional car at predetermined intervals, which comprises connecting the fluid conduit lines of the individual cars, supplying fluid to the

last car of the train when said train is in a predetermined position, inserting an additional car in said kiln, connecting the fluid conduit of the new car to that of the last car 5 of the train, connecting the conduit of the additional car to said source of fluid supply while maintaining the first connection to said supply, and disconnecting said first connection when said last car reaches a predetermined position.

8. A continuous tunnel kiln having a goods passageway extending longitudinally thereof, a plurality of kiln cars in said passageway carrying metallic articles to be heat 15 treated, a box on each car enclosing said articles, and means for continuously supplying a fluid to the interior of said boxes while in said passageway, said means comprising a pipe extending longitudinally of each of said 20 cars, a cut-off valve at each end of said pipe, a conduit connecting said pipe to the interior of said box, flexible conduit means connecting the adjacent pipe ends of adjacent cars, a source of fluid adjacent the entrance end 25 of the kiln, and a flexible conduit connecting the longitudinal pipe of a car adjacent said source to said source.

9. A continuous tunnel kiln adapted for annealing metallic articles and having a 30 goods passageway extending longitudinally thereof, a plurality of kiln cars in said passageway carrying metallic articles to be annealed, an annealing box on each car enclosing said articles, and means for continuously supplying a fluid gas to the interior 35 of said annealing boxes while in said passageway, said means comprising a pipe extending longitudinally of each of said cars, a cut-off valve at each end of said pipe, a conduit connecting said pipe to the interior of said box, a control valve in said conduit, flexible conduit means connecting the adjacent pipe ends of adjacent cars, a source of fluid adjacent the entrance end of the kiln, and a flexible 40 conduit continuously connecting the longitudinal pipe of a car adjacent said source to said source.

Signed at Cleveland, in the county of Cuyahoga and State of Ohio, this 20th day of 50 August, A. D. 1928.

PAUL A. MEEHAN.
